SWINGING DOOR LATCH

Stone E. Bush, United States Navy, and Gustave Miller, New Haven, Conn.

Application May 22, 1941, Serial No. 394,652

7 Claims. (Cl. 292—18)

(Granted under the act of March 3, 1883, as amended April 30, 1928; 370 O. G. 757)

This invention relates to a screen door latch, and has for an object to provide a safety latch especially intended for use on a door that swings in both directions from its closed position.

Swinging doors such as used in office buildings and elsewhere, are often a source of danger to persons who may be passing thereby just at a time that a person from the opposite side of the door may push the door outwardly in order to pass therethrough. This is especially so when a person is passing down a corridor leading past the swinging door if the door is open just as the person reaches that position, thereby possibly striking the person in the corridor in the face or elsewhere, with possibility of serious injury.

With this invention there is provided a latch that will prevent the door from swinging outwardly, and instead necessitate its being opened inwardly toward the person using the door. However, it must be realized that in some circumstances the swinging door should be swingable outwardly away from the person using the door, otherwise the entire purpose of the door being swingable to opposite sides may be lost. With this invention it is possible for the person using the door to nevertheless open the door outwardly by use of excessive pressure thereon.

With the foregoing and other objects in view, the invention consists in the construction, combination and arrangement of parts hereinafter described and illustrated in the drawing, in which:

Fig. 1 is a horizontal sectional view of a swinging door and door jamb to which this invention has been applied.

Fig. 2 is a vertical view of the latch of this invention at right angles to Fig. 1; and

Fig. 3 is a vertical view of the latch at right angles to Fig. 2, with the latch ear in raised position.

There is shown at 10 a swinging door mounted on double hinges 11 to the jamb 12 between an office 13 and the hall 14. Generally, the door swings freely past the opposite jamb 15, so that a person leaving office 13 pushing against the door 10 swings it out into hall 14, and is apt to injure a person walking down hall 14 just at that time. In some offices, the door 10 bears a notice "Pull," but such notice is often ignored or overlooked.

This invention comprises a double latch 16 mounted on jamb 15. Each individual latch ear 17 is identical but the reverse of the other. The latch ear 17 is provided at its inner edge 18 with a tubular bearing 19 through which extends a 55

pintle 20. Beyond its inner edge 18, the latch ear is curved as shown at 21, which curve 21 leads to the rounded point 22, from where there extends a cam edge 23 joining to the inner edge 18.

The pintle 20 has an eye 24 pivoted above a bearing 29 on a vertical journal 25. This journal 25 is mounted by an angular foot 26 to a plate 27 adapted to be secured to the door jamb 15 as by screws 28. A coil spring 30, of suitable strength, has one end affixed to the eye 24 of pintle 20 and its other end is anchored to the top of journal 25, so as to normally retain pintle 20 close along plate 27. A stop 32 fixed to the end of pintle 20 has a finger 33 extending into abutting relation with plate 27 to hold the pintle slightly spaced therefrom and permit latch bearing 19 to rotate about pintle 20. Another finger 34 on the stop 32 extends into a recess 35 in bearing 19, limiting the movement of ear 17 about pintle 20 and supporting it in horizontal position. Door 10 usually being of wood, striker plates 36 may be countersunk in the edge thereof of adjacent latch ear back 31 to reduce wear and friction therebetween.

In operation, when mounted as shown, door 10 on swinging shut, will cam up the latch ear 17 on the cam edge 23 and hit against the back 31 of the latch ear 17 on the far side and thus remain in a closed position. To open the door the near latch ear 17 is raised about its bearing 19, pivoting about pintle 20, permitting door 10 to be opened toward the operator. In an emergency such as a fire, or when one's hands are occupied, strong pressure against door 10 will cause it to press against the curve 21 of the back of the far latch ear 17, causing its pintle 20 to pivot about its eye 24 on journal 25 against the coil spring 30, to open the door on the far side.

While this invention has been described as applicable to a swinging door, it is obvious that it is equally applicable to a swinging gate or any other closure member which may normally be swung to opposite sides of its closed position.

Other modifications and changes in the number and arrangement of the parts may be made by those skilled in the art without departing from the nature of the invention, within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

1. A latch for a swinging closure member, said latch comprising a latch ear, means for pivoting said latch ear for vertical movement permitting said latch ear to be lifted out of the path of the swinging closure member, means for journaling said latch pivoting means permitting said latch ear and latch pivoting means to be rotated horizontally out of the path of the swinging closure member by pressure of the swinging closure member against said latch ear, and means for mounting said journal means on a closure member jamb adjacent the closure member.

2. A latch for a swinging closure member, said latch comprising a latch ear, means for horizontally pivoting said latch ear for vertical movement permitting said latch ear to be lifted out of the path of the swinging closure member, means vertically journaling said latch pivoting means permitting said latch ear and latch pivoting means to be rotated horizontally out of the path of the swinging closure member by pressure of the swinging closure member against said latch ear, and means for mounting said journal means on a closure member jamb adjacent the closure member.

3. A latch for a swinging closure member, said latch comprising a latch ear, means for pivoting said latch ear for vertical movement permitting said latch ear to be lifted out of the path of the swinging closure member, means for yieldably journaling said latch pivoting means permitting said latch ear and latch pivoting means to be rotated horizontally out of the path of the swinging closure member by pressure of the swinging closure member against said latch ear, said yieldable journal means restoring said latch ear to original position when said pressure is released, and means for mounting said journal means on a closure member jamb adjacent the closure member.

4. A latch for a swinging closure member, said latch comprising a latch ear, means for pivoting said latch ear for vertical movement permitting said latch ear to be lifted out of the path of the swinging closure member, a cam edge on the forward side of said latch ear cooperating with the closure member edge whereby said closure member may raise said latch ear and return to closed position, means for journaling said latch pivoting means permitting said latch ear and latch pivoting means to be rotated horizontally out

of the path of the swinging closure member by pressure of the swinging closure member against said latch ear, and means for mounting said journal means on a closure member jamb adjacent the closure member.

5. A latch for a swinging closure member, said latch comprising a latch ear, means for pivoting said latch ear for vertical movement permitting said latch ear to be lifted out of the path of the swinging closure member, a cam edge on the rearward side of said latch ear, means for journaling said latch pivoting means permitting said latch ear and latch pivoting means to be rotated horizontally out of the path of the swinging closure member by pressure of the swinging closure member against said rearward cam edge on said latch ear, and means for mounting said journal means on a closure member jamb adjacent the closure member.

6. A latch for a swinging door closure member, said latch comprising a latch ear, means for mounting said latch ear for vertical movement permitting said latch ear to be lifted out of the path of the swinging closure member, means for mounting said first mentioned mounting means for horizontal movement permitting said latch ear and said first mentioned latch mounting means to be moved horizontally out of the path of the swinging closure member by pressure of the swinging closure member against said latch ear, and means for mounting said second mentioned mounting means on a closure member jamb adjacent the closure member.

7. A latch for a swinging closure member, said latch comprising a latch ear, means for mounting said latch ear for movement in a plane parallel to the plane of the closure member when said closure member is in closed position, permitting said latch ear to be moved out of the path of the closure member, means for mounting said first mentioned latch mounting means for movement in a plane at right angles to the plane of said closure member when in closed position, permitting said latch ear and first mentioned mounting means to be moved out of the path of the swinging closure member by pressure of the swinging closure member against said latch ear, and means for supporting said second mentioned mounting means on a closure member jamb adjacent the closure member.
